UNITED STATES PATENT OFFICE.

WALTER B. WOORE, OF NEW YORK, N. Y.

SECONDARY VALVE.

1,383,180.

Specification of Letters Patent. Patented June 28, 1921.

Application filed April 26, 1920. Serial No. 376,756.

To all whom it may concern:

Be it known that I, WALTER B. WOORE, a citizen of the United States, and resident of New York city, in the county of New York and State of New York, have invented certain new and useful Improvements in Secondary Valves, of which the following is a specification.

The invention relates in general to a cut-off plug of the type in which an emergency secondary valve in a conduit is held off its seat by the positioning therein of a main valve faucet, plug or other valve unseating continuation of the construction, and in which the valve is seated automatically by the pressure of the fluid passing through the conduit and independent of springs or other movable parts which might deteriorate under conditions incidental to a long inactive use.

Specifically the invention relates to an improvement in secondary valves of the type disclosed in my pending application, Serial No. 327,766, renewed Oct. 1, 1919.

In certain situations where, for instance, there is a high pressure flow in the conduit controlled by the structure, with the resulting rapid movement of the valve element, it is vitally important that the valve whenever set in motion should contact firmly and squarely with its valve seat. Under conditions of varying high pressures, the slightest canting of the valve in moving onto its seat would defeat the desired instantaneous closing of the conduit so desirable in organizations of the type under consideration.

Accordingly, one of the basic objects of the invention is to provide a simple form of secondary valve of the class described and in which the valve element is guided squarely onto its seat when free of the restraining effect of the valve unseating element. I attain this object broadly by engaging the free sliding valve at two spaced apart bearing points preferably on opposite sides of the part of the valve which engages the seat.

Still another object of the invention is to provide a guiding structure which will at the same time limit the unseating movement of the valve, retain the valve in proximity to and oppositely disposed to its seat and in position immediately available to be forced onto its seat.

Still another object of the invention is to provide a device of the type disclosed in which the faucet or other coating valve un-

seating element can engage the valve to secure the same against vibration and thus defeat any tendency on the part of the valve to wear away the guiding member or its seat. 60

Various other objects and advantages of the invention will be in part obvious from an inspection of the accompanying drawings and in part will be more fully set forth in the following particular description of 65 one form of mechanism embodying my invention, and the invention also consists in certain new and novel features of construction and combination of parts hereinafter set forth and claimed. 70

In the accompanying drawings:—

Figure 1 is a view in axial section of a coupling constituting a preferred embodiment of my invention and operatively connected to a valve unseating member therein 75 shown to be a faucet disposed in position holding the valve structure in opened position.

Fig. 2 is a view similar to Fig. 1 with the faucet removed and the valve engaging its 80 seat.

Fig. 3 is a view in side elevation of the valvular structure shown in Figs. 1 and 2; and

Fig. 4 is a view in end elevation of the 85 guiding ring shown in Figs. 1 and 2.

In the following description and in the claims, parts will be identified by specific names for convenience of expression, but they are intended to be as generic in their 90 application to similar parts as the art will permit.

In the drawings there is shown a coupling 10 of conventional form provided with a bore 11 positioned within which is an annular valve seat 12 facing in the direction of flow of the fluid through the conduit which direction is indicated by the arrow in Fig. 1. The bore is threaded on opposite sides of the valve seat, the part 13 on the 95 advanced side of the valve seat adapted to receive a valve unseating insert 14 herein shown to be a nipple constituting the intake pipe of a faucet 15. The threads 16 on the rear side of the seat 12 are engaged by an 100 apertured guiding ring 17 which is designed to be located and adjusted by a rotating tool engaging in apertures 18 to position the ring in any desired spaced relation to the valve seat 12.

There is also disclosed a unitary floating valve construction 19 (see Fig. 3) which in-

cludes a conical valve proper 20 designed to engage the seat 12 and thus intercept the passage of the fluid through the conduit. The valve construction includes guiding extensions 21 and 22 projecting from opposite sides of the valve 20. The extension 21 projects forwardly through and beyond the valve seat 12, in position to be engaged by the member 14 and disposed so as to be held by said member in position to space the valve 20 a distance from the seat 12 just sufficient to provide a free passageway 23 about the valve as shown in Fig. 1.

The extension 22 is fitted within the bore 11 in the ring 17 so that the valvular construction is guided at two longitudinally spaced apart points, one provided by the inner edge 24 of the valve seat and the other provided by the ring 17. The extension 22 is 20 of hollow cylindrical form and has a relatively large diameter so as to provide an extensive annular bearing surface. The extension 22 is reduced from the diameter of the valve 20 to provide a stop shoulder 25 which 25 engages the forward side of the ring 17 and is limited thereby in its unseating movement. The parts are so proportioned that the shoulder 25 is held firmly seated against the ring by means of the member 14 engaging the 30 annular bearing faces 26 provided by the spaced apart arms forming the extension 21. Both of the extensions are provided with openings 27 to permit the passage of the fluid therethrough.

35 In operation and noting the position of the parts as shown in Fig. 2, it will be understood that the pressure of the fluid will act on the valve to securely seat the same in fluid tight engagement with the valve seat 40 and the fluid pressure acts on the entire rear face of the valve which is made as extensive as possible and is practically coextensive with the cross section of the threaded bore.

45 The insertion of the member 14 into position engaging the threads 18 will cause the advancing edge of the member 14 to squarely engage the forward bearing surface 26 of the valvular construction to move the same 50 axially of the bore and into engagement with the ring 17, in which position it is held by the engagement of the member 14 with the valve structure which in turn bears against the ring. The ring is positioned so as to 55 hold the valve firmly in the desired spaced relation to its seat and the positioning of the ring in the bore will be controlled largely by the character of the inserted member 14.

As soon as the member 14 is withdrawn, 60 the pressure of the fluid acting not only through the openings 18 but also acting axially against the central, major portion of the valve causes the same to snap quickly and positively onto its seat. The valve is guided in its seating position by its engagement

with both the valve seat and the rearwardly spaced guiding rings so that canting of the valve as it is moved into position is largely eliminated.

By means of a device of this character it 70 is possible to provide a secondary valve which in normal operation is held in fixed position spaced from but close to the valve seat immediately available to move promptly onto its valve seat as soon as the valve unseating element is removed from the coupling.

While I have shown and described, and have pointed out in the annexed claims, certain novel features of my invention, it will 80 be understood that various omissions, substitutions and changes in the form and details of the device illustrated and in its operation may be made by those skilled in the art without departing from the spirit of the 85 invention.

Having thus described my invention, I claim:

1. A coupling constituting an article of manufacture provided with a valve seat, a 90 valvular structure including a valve adapted to be normally closed onto said seat by the pressure of the fluid in the coupling, said valve provided with guiding means having forwardly extending portions extending through and beyond said seat in position and adapted to be engaged by a coupling-engaging element for positively holding the valve in spaced relation to its seat, said valve also provided with guiding 100 means comprising a rearwardly extending portion and means limiting the unseating movement of the valve and engaging said rearwardly extending portion for insuring a proper seating of the valve.

2. In a device of the class described, the combination of a conduit having two longitudinally spaced apart apertured partitions in the bore thereof, one of said partitions provided with a valve seat, and facing 110 the other partition and facing in a direction opposite to the direction of flow through the conduit, a floating secondary valvular device including a valve element adapted to be moved by the pressure of the flow on to said seat to intercept the flow through the conduit, and extensions for guiding the valve element to and from its seat, said extensions projecting longitudinally from opposite sides of the valve element and slidably mounted in and extending through the apertures in said partitions and a second conduit inserted in the first named conduit 115 and adapted to engage the adjacent extension to hold the valve element in spaced relation to its seat and thus permit a flow past the seat, both of said extensions provided with openings for permitting the flow to pass through the same.

3. In a device of the class described, the 120

125

combination of a conduit having two longitudinally spaced apart apertured partitions in the bore thereof, one of said partitions provided with a valve seat and the other

35
ably mounted in said ring and guided there-
by to effect a seating of the valve on said
seat when free of the valve unseating
member.

partition provided with an aperture to permit the passage of fluid therethrough, a floating secondary valvular device including a valve element positioned between said partitions and adapted to be moved by the pressure of the fluid onto said seat to intercept the flow through the conduit, and extensions for guiding the valve element to and from its seat, said extensions projecting longitudinally from opposite sides of the valve element and slidably mounted in and extending through the apertures in said partitions and means for securing a second conduit inserted in the first named conduit and said second conduit adapted to engage the adjacent extension to hold the valve element in spaced relation to its seat and thus permit a flow past the seat.

40
5. In a device of the class described, the combination of a member provided with a bore, a valve seat in said bore, a floating valve structure including a valve adapted to be normally closed onto said seat by the pressure of the fluid in said bore and provided with an extension adapted to be engaged by an insert introduced into the bore for holding the valve in unseated position, and guiding means for the structure adjustable relative to the seat to insure a proper seating of the valve and to limit the retreat 45
50 of the valve away from said seat under the influence of said insert.

4. In a device of the class described, the combination of a coupling having an annular valve seat in the bore, said bore being threaded on opposite sides of the seat, a guiding ring engaging the threads on one side of the seat and constituting a stop for limiting the unseating movement of a co-acting valve and the threads on the other side adapted to receive a valve unseating member, and a valvular structure including a valve for engaging said seat to close the bore and provided with an extension slid-

55
6. In a device of the class described, the combination of a conduit provided with a valve seat, of a valve adapted to fit said seat and adapted to be forced onto said seat by the fluid pressure in said conduit, a second conduit distinct from the first named conduit and adapted to bear on the valve and thus hold the valve off its seat and 60
65 means adjustable relative to the seat for guiding the valve in its closing movement onto its seat.

Signed at New York city, in the county of New York and State of New York, this 9th day of April, A. D. 1920.

WALTER B. WOORE.
